US00D858462S

(12) **United States Design Patent** (10) **Patent No.:** **US D858,462 S**
Lu (45) **Date of Patent:** **** Sep. 3, 2019**

(54) **TOUCH CONTROL BOX FOR LIFT TABLE**

(71) Applicant: **Dong Guan Song Wei Electric Technology Co., Ltd.**, Dongguan, Guangdong (CN)

(72) Inventor: **Weilin Lu**, Dongguan (CN)

(73) Assignee: **DONG GUAN SONG WEI ELECTRIC TECHNOLOGY CO., LTD.**, Dongguan, Guangdong (CN)

(**) Term: **15 Years**

(21) Appl. No.: **29/650,807**

(22) Filed: **Jun. 10, 2018**

(51) LOC (12) Cl. **13-03**

(52) U.S. Cl. **USPC .....** **D13/164**

(57) **CLAIM**

The ornamental design for a touch control box for lift table, as shown and described.

DESCRIPTION

FIG. 1 is a perspective view of a touch control box for lift table showing my present design;

FIG. 2 is a front view thereof;

FIG. 3 is a left side view thereof;

FIG. 4 a right side view thereof;

FIG. 5 is a top view thereof;

FIG. 6 is a bottom view thereof; and,

FIG. 7 is a perspective view showing that the touch control box is mounted to the lift table.

The broken lines showing of the lift table is for illustrative purposes only and forms not part of the claimed design.
